UNITED STATES PATENT OFFICE

2,175,904

ELECTRIC CUT-OUT

George F. Lincks, Pittsfield, Mass., assignor to
 General Electric Company, a corporation of
 New York

Application December 11, 1937, Serial No. 179,324

22 Claims. (Cl. 200—126)

The present invention relates to electric cut-outs and has for an object the provision of an improved fuse cut-out of the automatic circuit reclosing type.

5 Another object of the invention is the provision of a circuit reclosing fuse unit of improved construction and arrangement of parts for use in an electric cut-out.

10 A still further object of the invention is the provision of improved mechanism for carrying out the inventions forming the subject matter of United States Letters Patent No. 2,164,994, issued July 4, 1939, in my name, and United States Letters Patent No. 2,165,015, issued July 4, 1939, 15 in the name of L. P. Sohles, both of which patents are assigned to the assignee of the present invention.

20 Other objects and the details of that which I believe to be novel and my invention will become apparent from the following description and the claims appended thereto, taken in conjunction with the accompanying drawing. While my invention may be incorporated in cut-outs of either the open type or the enclosed type, as will become 25 apparent hereinafter, I have chosen as the best means of conveying a complete understanding of all of the features of the invention to illustrate and describe an exemplary embodiment thereof as incorporated in a fuse cut-out of the enclosed 30 type.

In the drawing, Fig. 1 is a sectional view of the exemplary cut-out showing the parts thereof in their normal operative positions; Fig. 2 shows the relative positions of the parts of the cut-out 35 after operation of one of the fuses therein, and Fig. 3 shows the positions of the parts after operation of the final one of the fuses therein.

40 Referring to the drawing, 10 indicates an electric cut-out casing of the type commonly employed in non-reclosing fuse cut-out installations. This casing is constructed of porcelain or other suitable insulating material and has an integrally formed electric creepage and gas barrier 11 provided with a groove 12 for receiving the innermost fuse holder described hereinafter. A mounting bar 13 is secured to the rear of the casing for attachment thereof to a suitable supporting structure. Secured to the inner face 45 of the rear wall of the casing respectively on the upper and lower sides of barrier 11 are line terminal contacts 14 and 15 to which line leads may be secured by screws 14' and 15' respectively. Also secured to the rear wall of the casing adjacent the bottom thereof is a hinge bracket 16

having a hinge pin 17. Upper contact 14 has a downwardly pressing contact finger 20 backed by a spring strip 21 and has also a pair of spaced resilient contact fingers 22, the nearer one of which fingers 22 is shown in the drawing.

5 In accordance with the teachings of the hereinbefore identified patents of myself and of L. P. Sohles, a special form of door 23 is provided for closing the open front of casing 10. This door has a recessed inner side for receiving a fuse 10 holder assembly and circuit reclosing mechanism to be described hereinafter, which assembly and mechanism would project beyond the open front of a cut-out casing, such as the one illustrated, primarily designed for non-reclosing cut-out installations and having sufficient depth to accommodate only a single fuse holder. On the outer face of the door is an integrally formed eyelet handle 24 adapted to be engaged for swinging the door, fuse holder assembly, and circuit reclosing 20 mechanism into and out of the normal operative position illustrated in Fig. 1. The inner face of the door is formed also with a compartment 25 adjacent the lower edge of the door and the front of this compartment is closed by means of 25 a metal plate 26 bearing against the inner face of the door and secured thereto by means of one or more screws 27. Projecting inwardly from plate 26 substantially at right angles to the door is a fuse holder supporting and guiding arm 30 30 of good conductivity metal, upon the inner end of which is pivotally mounted a spring biased contact arm 31 arranged to bear against contact 15. Arm 30 has a pair of vertically extending bores in the innermost one of which is secured, 35 by means of screw 32, a downwardly depending sleeve 33 of insulating material. A terminal collar 34 is mounted on the lower end of sleeve 33 and fastened thereto by means of a screw 35. This collar has an inwardly projecting arm to 40 which is secured, by means of screws 36 and 39, a hinge element or toggle lever 37 which has a hook-shaped portion 38 arranged to engage hinge pin 17. The upper screw 36 is arranged to provide a pivotal connection between toggle lever 45 37 and the outwardly projecting arm of collar 34, while screw 39 is adapted to be removed to permit relative movement between the toggle lever and the collar. When screw 39 is in place as illustrated in the drawing, it serves as a locking element to prevent relative movement between the toggle lever and the collar, and under these conditions door 23, plate 26, arm 30, sleeve 33, collar 34, and lever 37 form a rigid structure 50 arranged to rotate as a unit about hinge pin 17. 55

In order to secure the upper end of the door in closed position, there is secured to the inner face of the door adjacent the top thereof an inwardly projecting electrically conductive arm 40 having on its inner end a rounded head portion 41 arranged to be engaged by spring contact fingers 20 and 22 for latching the upper end of the door in closed position. A metallic spring strip is fastened on the lower side of arm 40 by means of a rivet 42 or other suitable means and has a pair of contact fingers 43 and 44 extending inwardly and outwardly respectively from the point of attachment of the spring strip. These contact fingers 43 and 44 are arranged normally to bear downwardly respectively on the contact caps 45 and 46 on the upper ends of fuse holders 47 and 48 respectively.

Only two fuse holders are employed in the embodiment illustrated, but, as will become apparent hereinafter, the invention may be practiced with more than two fuse holders if desired. Of the pair of fuse holders illustrated, the innermost one, 47, is mounted for longitudinal vertical sliding movement in sleeve 33, while the outermost holder, 48, is mounted for longitudinal vertical sliding movement in the outer bore of supporting arm 30. Fuse holder 47 is latched in its upper normal operative position by means of an extension 50 of a fuse link disposed in holder 47 and connected with cap 45, the said extension 50 being passed around a boss 51 on the lower end of hinge element 37 and secured to terminal collar 34 by means of any suitable form of clamping means indicated at 52. As will be evident from the drawing, the fuse link in holder 47 normally is electrically isolated from contact 15 due to the insulating sleeve 33 extending between conductive collar 34 and conductive arm 30. Fuse holder 48 normally is latched in its upper operative position by means of a hook arm 53 which engages the lower end of holder 48 and the mounting of which will become apparent from the ensuing description.

On the lower end of the plate 26, which as previously described is secured to the inner face of door 23, there are provided two spaced arms 55, the nearer one of which is shown in the drawing, and these arms serve to support a pivot pin 56 upon which is pivotally mounted a fuse terminal 57. This terminal is biased to swing in a counterclockwise direction by means of a helical spring 58 disposed about pivot pin 56. The terminal normally is latched in its position illustrated in Fig. 1 by securing thereto, by means of a winged clamping screw 60, the end 61 of a fuse link extending out of the lower end of holder 48. The upper end of such fuse link is anchored in the upper end of holder 48 and is electrically connected with contact cap 46. Normally, therefore, the fuse link in holder 48 is electrically connected between contacts 14 and 15, the circuit extending from contact fingers 20 and 22 through the contact engaging head 41 and arm 40, contact finger 44, cap 46, the fuse link in holder 48, fuse link extension 61, terminal 57, pivot pin 56, arms 55, plate 26, fuse holder supporting arm 30, and the spring biased contact arm 31 to lower stationary contact 15.

In order to secure circuit reclosure upon operation of the fuse link in holder 48, there is provided an improved and compact time delayed circuit reclosing mechanism of the type disclosed in the previously referred to patent of L. P. Sohles. Since the details of this circuit reclosing mechanism are fully set forth in the said

Sohles patent, only sufficient of these details will be described herein to give a proper understanding of the operation of the illustrated cut-out and of the improvements which I have made in certain elements of the Sohles mechanism. On the inner face of plate 26 there is secured by means of screws 62 a guide element 63 which is arranged to support a vertically slideable switch supporting element 64. This switch supporting element is arranged to be biased downwardly by means of a coiled compression spring 65 which bears against the lower face of arm 30 and is reinforced against buckling by means of rod 66. The lower end of element 64 carries a pivot pin 67 upon which is pivotally supported a switching element 68. A helical spring 69 is disposed on pivot pin 67 and arranged to bias the switching element for counterclockwise rotation. The switching element, as described in detail in the said Sohles patent, is substantially U-shaped and has a pair of spaced contact arms 70 arranged to pass on opposite sides of holder 48. Normally switch supporting element 64 and switching element 68 are maintained in raised positions, as illustrated in Fig. 1, by means of a pair of spaced detent fingers 71, one of which is shown in the drawing. These fingers are carried by the pivotally mounted spring biased terminal 57 and are arranged to engage the lower end of switching element 68, the fingers being held normally in latching position against the action of spring 58 by connection of fuse link extension 61 with terminal 57, as previously described. Switching element 68 has a downwardly extending portion 72 arranged to be received between detent fingers 71 and upon the lower end of this extension 72 is mounted the hook arm 53 for latching holder 48 in normal operative position. A shunt strip 73 is connected between terminal 57 and switching element 68 for carrying current to the switching element. Spring 69 tends to effect counterclockwise rotation of contact arms 70 into engagement with contacts 14 on terminal collar 34, as indicated in Fig. 2, but such counterclockwise rotation of the contact arms is prevented when the contact arms are in their raised positions by engagement of the arms with detents 75, one of which may be seen in the drawing, which are mounted on opposite sides of the fuse holder supporting arm 30 and extend downwardly from this arm. In order to delay downward movement of switch supporting element 64 upon release thereof, there is provided a mechanical escapement type timing mechanism of the type described in the previously referred to patent of L. P. Sohles. The gears and inertia arm of this timing mechanism are disposed in compartment 25, as indicated at 76, and this timing mechanism is connected with switch supporting element 64 in a manner to retard the downward movement thereof.

Upon operation of the fuse link in fuse holder 48, which fuse link, as previously set forth, is normally connected between contacts 14 and 15, terminal 57 is released to swing outwardly due to the bias of spring 58 and the pressure exerted by downwardly spring biased switching element 68 against detent fingers 71, which fingers are off center with respect to the pivotal mounting of terminal 57. This outward movement of terminal 57 causes disengagement of detent fingers 71 from switching element 68 so that switch supporting element 64 and switching element 68 are free to move downwardly under the influence of spring 65 except for the delaying

action of timing mechanism 76. After a predetermined downward movement of element 64, the upper ends of contact arms 70 become disengaged from detents 75. The contact arms are then 5 rotated in a counterclockwise direction into engagement with contacts 14 by means of spring 69. The counterclockwise rotation of switching element 68 causes disengagement of hook arm 53 from fuse holder 48 so that this holder may 10 drop downwardly to the position indicated in Fig. 2 wherein the contact cap 46 on the upper end of the holder is disengaged and spaced a considerable distance from contact finger 44. Also, the engagement of contact arms 70 with contacts 15 74 effects reclosure of the circuit through the fuse link in fuse holder 47, the circuit extending from contact fingers 20 and 22 through contact engaging head 41, arm 40, contact finger 43, contact cap 45, the fuse link in fuse holder 47, 20 fuse link extension 50, terminal collar 34, contacts 14, contact arms 70, shunt strip 73, terminal 57, pivot pin 56, arms 55, plate 26, fuse holder supporting arm 30, and the spring biased contact arm 31, to lower stationary contact 15. 25 Subsequent to operation of the fuse link in holder 48 and while the fuse link in holder 47 still is intact, the door and fuse holder assembly may be removed for refusing of holder 48. This may be accomplished readily by pulling outwardly 30 on handle 24 to disengage contact engaging head 41 from contact fingers 20 and 22 and then rotating the assembly about hinge pin 17 to a point where lever 37 may be disengaged from the hinge pin. After removal of the door and fuse holder 35 assembly from casing 10, fuse link extension 50 may be released to permit holder 47 to drop so as to give access to contact cap 46 with the holder 48 in its position shown in Fig. 2. After installation of a new fuse link in holder 48, the 40 circuit reclosing mechanism and fuse holders are reset and the door and fuse holder assembly replaced in casing 10 in the manner described more in detail hereafter.

In case the rupture of the fuse link in fuse 45 holder 48 is due to a temporary fault, it is desirable that some time delay be afforded before reclosure of the circuit through the fuse link in fuse holder 47 so that the fault current may be completely interrupted in fuse holder 48. Otherwise, the fuse links in both of the fuse holders would operate on a single temporary fault which required an appreciable time to clear after rupture of the fuse link in holder 48. Also, the 50 time delay has a distinct advantage in that it makes possible to closer coordination between fuse links connected in series at sectionalizing points and fuse links connected in series with induction type relays. The desired time delay in the circuit reclosure is provided, as previously 55 set forth, by the timing mechanism 76. In order that the amount of time delay may be adjusted as desired in accordance with conditions encountered, I provide means for adjustment of the extent to which element 64 must move downwardly 60 before contact arms 70 are released from detents 75. To this end, detent fingers 71 are provided with elongated slots 80 for receiving the screws 65 81 by which the fingers are secured to terminal 57, so that the fingers may be adjusted vertically. With screws 81 at the lower ends of slots 80, as indicated in the drawing, the detent fingers serve 70 to hold contact arms 70 in their extreme uppermost positions so that a greater downward movement thereof will be required to release the con-

tact arms from detents 75, thus providing a longer time delay. If detent fingers 71 are moved downward so that screws 81 are in the upper ends of slots 80, contact arms 70 normally will be latched in a lower position so that less downward movement thereof will be required to release the contact arms from detents 75 and thus a shorter time delay will be provided. With fingers 71 in their lowermost positions, fuse holder 48 also is maintained in a lowered position by hook arm 53. Upper spring contact finger 44 may be given such form and tension that it will maintain contact with contact cap 46 notwithstanding the lowered position of holder 48. A further time delay adjustment is provided in that detents 75 have elongated slots 82 for receiving screws 83 by which the detents are secured to supporting arm 30. With screws 83 in the upper end of slots 82, as illustrated, detents 75 are maintained in their lowermost positions so that a greater downward movement of contact arms 70 is required for release of the contact arms from the detents. By adjusting the detents 75 upwardly, less downward movement of the contact arms will be required and thus less time delay will be secured. Hence, by vertical adjustment, both of detent fingers 71 and detents 75 a relatively wide range of adjustment of the time delay of circuit reclosure is made possible.

In order to insure against reclosure of the circuit through the fuse link in holder 47 due to arc-over between the lower ends of holders 47 and 48 upon discharge of arc gases from holder 48, holder 48 is made longer than holder 47 and is arranged to project substantially below the lower end of holder 47 in accordance with the teachings of United States Letters Patent No. 2,169,087, issued August 8, 1939, in the name of R. S. Bennett, and assigned to the assignee of the present invention. As a result of this expedient, it takes longer for the arc gases to mushroom and eddy up from the lower end of holder 48 into proximity with the conducting parts at the lower end of holder 47 and this additional time allows for cooling of the gases, so 45 that they are less conducting, and for proper clearing of a temporary fault current in holder 48 and proper reclosure of the circuit by means of the time delayed circuit reclosing mechanism. Also, in accordance with the teachings of the 50 said patent of R. S. Bennett, a barrier plate 85, preferably of insulation material, is disposed on top of fuse holder supporting arm 30 just beneath the barrier 11 of casing 10. This barrier plate 55 has an opening through which the fuse holders pass and extends transversely of the fuse holders into close proximity with the walls of casing 10 and door 23, so as to supplement the action of barrier 11 and effect substantially complete isolation from each other of the spaces around contacts 14 and 15. Thus, arc gases discharged from the lower ends of holders 47 and 48 are 60 greatly retarded, if not entirely prevented, from rising into the upper portion of the cut-out housing around contact 14 so as to bridge the terminals of the cut-out.

After reclosure of the circuit through the fuse link in holder 47 by means of contact arms 70, as previously described, and in case of continuing 70 or recurring fault, the fuse link in holder 47 will rupture, thereby to cause fuse link extension 50 to release holder 47 so that this holder may drop to its position indicated in Fig. 3 wherein contact cap 45 is disengaged and electrically isolated 75

from contact finger 43 and wherein the downward projection of holder 47 gives clear indication of operation of the last of the fuse links. If, in the installation of the door and fuse holder assembly in casing 10, the locking screw 39 is left out of the supporting hinge means comprised of toggle lever 37 and the inwardly projecting arm of collar 34, rupture of the fuse link in holder 47 also will cause release of the toggle lever by fuse link extension 50 so that the toggle mechanism may collapse in the well known manner. This permits the door and fuse holder assembly as a unit to drop downwardly and then swing outwardly and downwardly to complete dropped-out position in the manner described in detail in the previously referred to patent of L. P. Sohles. With the assembly in complete dropped-out position, an additional clearly observable indication is given of operation of all of the fuse links.

Subsequent to operation of the fuse links in both of the fuse holders, or to operation of the fuse link in holder 47 after previous operation of the fuse link in holder 48, door 23 and the fuse holder assembly supported thereby may be removed from casing 10 in the manner previously described in connection with removal of the door and fuse holder assembly after operation of only the first fuse link. Replacement of the ruptured fuse links in the fuse holders by new fuse links may be accomplished readily when the fuse holders are in the positions illustrated in Fig. 3, relative to the door, wherein contact caps 45 and 46 are easily accessible. After installation of the new fuse links and replacement of caps 45 and 46, holder 47 is moved upwardly until cap 45 engages and tensions spring contact finger 43. Then fuse holder 47 is latched in its operative position by clamping the fuse link extension 50 to terminal collar 34. Also, holder 48 is moved upwardly into its operative position wherein its contact cap 46 engages and tensions contact finger 44. Holder 48 then is latched in operative position by rotation of switching element 68 into parallel relationship with switch supporting element 64 and movement of the switching element and supporting element upwardly against compression spring 65 until hook arm 53 engages the lower end of holder 48. Contact arms 70 are then held in open circuit position relative to terminal contacts 74 by detents 75, and switching element 68 is latched in its raised position by swinging terminal 57 toward holder 48 until detent fingers 71 engage the lower end of the switching element in the manner previously described. The terminal element is latched by securing thereto the portion 61 of the fuse link extending out of the lower end of holder 48. The parts of the circuit reclosing fuse unit are then in their positions illustrated in Fig. 1 and the unit may be installed in the cut-out casing by engaging hinge element 31 with hinge pin 17 and rotating the unit upwardly until contact engaging head 41 is latched by means of spring contact fingers 22 and spring backed contact finger 20.

From the foregoing description, it will be apparent that I have provided a circuit reclosing apparatus having an improved and compact construction and arrangement of parts and which may be furnished to electric operating companies and the like in the form of a single unit embodying a plurality of fuse holders, circuit reclosing mechanism, and time delay mechanism with the necessary connections and means for removably mounting the unit on a cut-out supporting structure of standard design. Such a unit has, among

others, the advantages that it may be used as a replacement for similar units or may be made interchangeable with fuse units of the non-reclosing type so that, without modification of the cut-out supporting structure and stationary contacts carried thereby, an electric cut-out of the non-reclosing type may be converted readily to one of the reclosing type, or vice versa, without the necessity for removal of the cut-out supporting structure from the line pole or the like upon which the supporting structure is mounted in the field.

It will be apparent also to one skilled in the art that my present invention in its broader aspects is not limited to the particular details of the exemplary cut-out illustrated. For example, by simple modifications well within the range of mechanical skill, the illustrated reclosing fuse unit may be adapted for use also in cut-outs of the open type.

What I claim as new and desire to secure by Letters Patent of the United States, is:

1. In an electric cut-out, an insulating support, a pair of terminals carried thereby, a fuse assembly removably mounted on said support and including a plurality of fuse holders and common supporting means therefor arranged to provide for bodily longitudinal movement of the holders relative to said terminals, means for normally latching said holders in operative positions, means for connecting a fuse link in one of said holders between said terminals and means operative responsively to operation of the fuse link in said one holder for completing an electric connection of a fuse link in the other of said holders between said contacts, said latching means being operative to release each of said holders upon operation of the fuse link therein for bodily movement of the holder to a position isolated electrically from at least one of said terminals.

2. In an electric cut-out, the combination with an insulating support having spaced terminals, of a circuit reclosing fuse unit comprising a plurality of fuse holders, a common supporting structure for said holders arranged to guide the holders for bodily movement relative to the supporting structure, means for latching the holders against bodily movement and in normal operative positions, said latching means being arranged to release each of said holders for bodily movement upon operation of a fuse link therein, means for mounting said supporting structure and holders on said insulating support with the holders disposed for successive connection of fuse links in the respective holders between said terminals, means for connecting a fuse link in one of said holders between said terminals, and circuit reclosing mechanism carried by said supporting structure operative responsively to operation of a fuse link in said one holder for completing an electric connection of a fuse link in another of said holders between said contacts, each of said holders upon release thereof by said latching means being movable bodily to a position wherein the holder is electrically isolated from at least one of said terminals.

3. In a circuit reclosing fuse unit for installation on an electric cut-out support of the type having a pair of spaced terminal contacts, a plurality of fuse holders and common supporting means therefor arranged for bodily longitudinal movement of the holders relative to said supporting means, means for latching said holders against such movement and in normal operative positions, means for mounting said supporting

means and holders on a cut-out support of the above said type, means for connecting a fuse link in one of said holders between the stationary contacts of the cut-out support, and circuit reclosing mechanism operative for completing an electric connection of a fuse link in another of said holders between the stationary contacts of the cut-out support upon rupture of the fuse link in said one holder, said latching means being operative to release each of said holders upon rupture of the fuse link therein for bodily movement of the holder.

4. In an electric cut-out, a first stationary contact device, a second stationary contact device, a fuse assembly including a pair of fuse holders each having a terminal for connection with one end of a fuse link therein, supporting means for said holders arranged for bodily longitudinal movement of the holders relative to said contact devices, means for maintaining said holders in normal operative positions with said fuse holder terminals engaging said first contact device, said maintaining means being operative upon rupture of a fuse link in each of the holders to release the holder for bodily movement, means for connecting the other end of a fuse link on one of said holders with said second contact device, and circuit reclosing mechanism operative upon rupture of a fuse link in said one holder for completing an electric connection between said second contact device and the other end of a fuse link in the other of said holders, each of said holders upon release thereof by said maintaining means being movable longitudinally to disengage its corresponding terminal from said first contact device.

5. In an electric cut-out including an insulating support and spaced contact terminals mounted thereon, a circuit reclosing fuse unit removably mounted on said support and including a contact device arranged removably to engage one of said terminals, a fuse assembly including a pair of fuse holders and common supporting means therefor, each of said holders having a terminal arranged for connection with one end of a fuse link in the holder and for engagement normally with said contact device and said fuse holder supporting means being arranged for bodily longitudinal movement of the holders for disengagement of said terminals from said contact device, latching means for normally preventing such movement of the holders, means for connecting the other end of a fuse link in one of said holders with the other of said spaced contact terminals and means operative upon rupture of the fuse link in said one holder for completing an electric connection between said other terminal and the other end of a fuse link in the other of said holders, said latching means being operative to release each of said holders upon rupture of the fuse link therein.

6. A circuit reclosing fuse unit comprising a plurality of fuse holders each having a terminal for connection with one end of a fuse link therein, a supporting structure for said holders arranged to provide for bodily movement of the holders relative to the supporting structure, means for mounting said supporting structure and holders on an electric cut-out support having an upper and a lower stationary contact, an upper and a lower contact engaging device carried by said supporting structure for engagement respectively with the upper and lower stationary contact of a cut-out support, latching means for maintaining said holders in operative positions with their said

terminals engaging said upper contact engaging device, said latching means being arranged to release each of said holders for bodily movement thereof upon operation of a fuse link therein, means for connecting the other end of a fuse link in one of said holders with said lower contact engaging device and means operative responsive to operation of a fuse link in said one holder for completing an electric connection between said lower contact engaging device and the other end of a fuse link in another of said holders, each of said holders upon release thereof by said latching means being movable bodily to disengage its corresponding terminal from said upper contact engaging device.

7. In an electric cut-out of the circuit reclosing type, a housing including a casing having an open side and a door mounted for closing said open side, spaced stationary terminals in said housing, a plurality of fuse holders, means including said door for supporting said holders in said housing and arranged for bodily longitudinal movement of the holders relative to said terminals, means for latching said holders in normal operative positions and arranged to release each of said holders for bodily movement upon rupture of a fuse link therein, and means for successively connecting fuse links in the respective holders between said terminals, each of said holders upon release thereof by said latching means being movable longitudinally to a position wherein the holder is disconnected from at least one of said terminals.

8. In an electric cut-out, a housing comprising a casing having an open side and a door removably mounted for closing said open side, a pair of terminal contacts mounted in said casing, a contact device carried by said door and arranged to engage one of said terminal contacts, a fuse assembly in said housing and including a pair of fuse holders with common supporting means therefor, said supporting means providing for bodily longitudinal movement of said holders relative to said contact device, each of said holders having a terminal for connection with one end of a fuse link in the holder, means for latching said holders in normal operative positions with said terminals engaging said contact device, means for connecting the other end of a fuse link in one of said holders with the other of said terminal contacts and circuit reclosing mechanism operative upon rupture of the fuse link in said one holder for completing an electric connection between said other terminal contact and the other end of a fuse link in said other holder, said latching means being operative to release each of said holders upon operation of the fuse link therein for longitudinal movement of the holder to disengage its corresponding terminal from said contact device.

9. In an electric cut-out of the circuit reclosing type, a housing comprising a casing and a door removably mounted for closing an open side of the casing, spaced terminals mounted in the casing, a plurality of fuse holders, means mounted on the inner side of said door for supporting said holders in said housing, said holders being bodily longitudinally movable relative to said terminals, means for latching said holders in normal operative positions, and means for successively connecting fuse links in the respective holders between said terminals, said latching means being operative upon rupture of a fuse link in each of said holders to release the holder for longitudinal

movement thereof to a position electrically isolated from at least one of said terminals.

10. In an electric cut-out of the circuit reclosing type, a housing comprising a casing having an open front and a door removably mounted for closing said open front, spaced terminals mounted in the casing, a plurality of fuse holders, supporting means for said holders including a guide member attached to and projecting inwardly from the inner side of said door, said member being arranged to maintain the holders with their axes lying substantially in a plane normal to the rear wall of said casing and to provide for bodily longitudinal movement of the holders relative to said terminals, means for latching the holders in normal operative positions, and means for successively connecting fuse links in the respective holders between said terminals, said latching means being operative to release each of said holders upon rupture of a fuse link therein for longitudinal movement of the holder to a position electrically isolated from at least one of said terminals.

11. An automatic circuit reclosing fuse unit adapted for removable installation in an electric cut-out casing and comprising a door adapted to close an open side of an electric cut-out casing, a first and a second contact device arranged respectively to connect with a pair of stationary terminals in an electric cut-out casing, a fuse assembly including a plurality of fuse holders and means for supporting the holders on the inner side of said door, each of said holders having a terminal normally engaging said first contact device and arranged to connect with one end of a fuse link in the holder, said supporting means being arranged for bodily longitudinal movement of the holders to disengage said terminals from said first contact device, means for latching said holders in their normal operative positions, and means for successively electrically connecting the other ends of fuse links in the respective holders with said second contact device, said latching means being arranged to release each of said holders for longitudinal movement upon rupture of a fuse link therein.

12. In an electric cut-out, an insulating support having spaced stationary terminals, a fuse assembly including a pair of fuse holders and a common supporting structure therefor removably mounted on said insulating support, said structure including an electrically conductive element electrically connected with one of said terminals and having means for receiving and slidably guiding said holders, means for latching said holders against sliding and in normal operative positions, a terminal contact carried by said supporting structure and insulated from said element, means for normally electrically connecting a fuse link in one of said holders between the other of said stationary terminals and said element, means for normally electrically connecting a fuse link in the other of said holders between said other stationary terminal and said insulated contact, and circuit reclosing switching means operative upon rupture of a fuse link in said one holder for completing an electric connection between said insulated contact and said element, said latching means being operative to release each of said holders upon rupture of a fuse link therein for longitudinal sliding of the fuse holder to effect electrical isolation thereof from at least one of said stationary terminals.

13. In an electric cut-out, an insulating support having spaced stationary terminals, a pair

of fuse holders, a common supporting structure for said holders including an electrically conductive element having means for receiving and slidably guiding said holders and an insulating member rigidly attached to said element and having mounted thereon in insulated spaced relation to said element a contact terminal and means for mounting said supporting structure on said insulating support, said element having means arranged to connect electrically with one of said stationary terminals, latching means normally restraining said holders from sliding relative to said element and in operative positions, means for connecting a fuse link in one of said holders between said element and the other of said stationary terminals, means for connecting a fuse link in the other of said holders between said contact terminal and said other stationary terminal, and circuit reclosing mechanism carried by said supporting structure and operative upon rupture of a fuse link in said one holder for completing an electric connection between said contact terminal and said element thereby to reclose a circuit through the fuse link in said other holder, said latching means being operative to release each of said holders for longitudinal sliding upon rupture of the fuse link therein.

14. In an electric cut-out, the combination with an insulating support having a hinge bracket and an upper and a lower terminal contact, of a circuit reclosing fuse unit including a pair of fuse holders, an electrically conductive member having means receiving and guiding said holders for substantially vertical longitudinal movement relative to said terminal contacts, an insulating sleeve attached at one end to said member and extending in surrounding relation to one of said holders, a terminal collar mounted on the other end of said sleeve and having attached thereto a hinge element for engagement with said hinge bracket, means for latching said holders against sliding and for maintaining the holders in normal operative positions, means for connecting the upper ends of fuse links in said holders with said upper contact, means for connecting said member with said lower contact, means for connecting the lower end of a fuse link in said one holder with said collar, means for connecting the lower end of a fuse link in the other of the holders with said member, and circuit reclosing mechanism operative responsively to operation of a fuse link in said other holder for completing an electric connection between said member and said collar, said fuse holders upon rupture of fuse links therein being released by said latching means and movable downwardly to positions electrically isolated from said upper contact.

15. In an electric cut-out, an insulating support, spaced terminals carried thereby, a fuse assembly including a pair of fuse holders and common supporting means therefor, means including a toggle lever hingedly mounted at one end on said support and pivotally connected at the other end with said assembly for supporting said assembly on said support removably in normal operative position relative to said terminals, said lever being held normally in fixed relation to said assembly, one of said holders being supported for bodily longitudinal movement relative to said supporting means and out of its normal operative position, means for restraining said one holder against longitudinal movement and in normal operative position, said restraining means being operative to release said one holder upon rupture of a fuse link therein, means for connecting a

- fuse link in said one holder between said terminals, and means operative responsively to rupture of a fuse link in said one holder for completing a connection of a fuse link in the other of said holders between said terminals, said toggle lever being releasable by operation of a fuse link in said other holder to provide for movement of said assembly as a unit from its said normal operative position.
16. In an electric cut-out of the circuit reclosing type, a pair of stationary terminals, a fuse holder supported normally for connection of a fuse link therein between said terminals and arranged for bodily longitudinal movement relative to the terminals, circuit reclosing mechanism including a switching element normally disposed in open circuit position, detent means carried by said switching element operative to latch said holder in normal connected position when said element is in open circuit position and operative to release said holder upon movement of said element toward closed circuit position, and means operative upon rupture of a fuse link in said holder for effecting movement of said element to closed circuit position, said holder upon release thereof by said detent means being longitudinally movable to a position electrically isolated from one of said terminals.
17. In an electric cut-out, the combination with a pair of stationary terminals and a fuse holder supported normally for connection of a fuse link therein between said contacts and arranged for bodily longitudinal movement relative to the terminals, of circuit reclosing mechanism including a member guided for movement in a direction substantially parallel with said holder, a switch element movably mounted on said member and spring biased to closed position, a detent mounted for holding said element in open position when said member is in a first position, means carried by said element operative to restrain said holder in connected position when said member is in its said first position and said element in its said open position, means for latching said member in its said first position and arranged to release said member upon operation of a fuse link in the holder, means operative upon release of said member for effecting movement thereof toward a second position to release said element from said detent, said element upon release being movable toward closed position so as to cause release of said holder by said restraining means, and timing mechanism connected for delaying movement of said member toward its said second position.
18. In combination, a switch supporting member, a switching element movably mounted thereon and spring biased to a circuit controlling position, a detent mounted for holding said element in another position when said member is in a first position, releasable latching means for holding said member in its said first position, means operative upon release of said latching means for effecting movement of said member toward a second position to disengage said switching element from said detent, and timing mechanism connected for delaying movement of said member toward its said second position, said detent being adjustably mounted for movement substantially in the direction of movement of said member so as to provide for adjustment of the movement of said member required to effect release of said element from the detent.
19. In combination, a switch supporting member, a switching element movably mounted there-
- on and spring biased to a circuit controlling position, a first detent mounted for holding said element in another position when said member is in a first position, releasable latching means including a second detent arranged to restrain said member in its said first position, means operative upon release of said member for effecting movement of said member toward a second position to disengage said switching element from said first detent, and timing mechanism connected for delaying movement of said member toward its said second position, said second detent being adjustably mounted for movement substantially in the direction of movement of said member so as to provide for adjustment of the said first position of said member and thereby the amount of movement of said member required to effect release of said element from said first detent.
20. In an electric cut-out of the circuit reclosing type, the combination with a pair of stationary terminals and a fuse holder normally supported for connection of a fuse link therein between said terminals, of circuit reclosing mechanism including a movably mounted switch supporting member, a switching element movably mounted on said member and biased to closed position, a first detent mounted for holding said element in open position when said member is in a first position, a movably mounted terminal having a second detent operative releasably to restrain said member in its said first position, said second detent being held in its restraining position by connection of a fuse link in said holder with said movably mounted terminal, said second detent being adjustably supported on said terminal for movement substantially in the direction of movement of said member so as to provide for adjustment of the said first position of said member, and means operative upon release of said member by said second detent for effecting movement of said member toward a second position to disengage said switching element from said first detent.
21. In an electric cut-out of the circuit reclosing type, a support having spaced terminals, a fuse assembly removably mounted on said support and including a fuse holder having a fuse link electrically connected between said terminals and a supporting structure for said holder, and circuit reclosing means carried by said structure, which means includes a movable mounted switch supporting member, a switching element movably mounted on said member and biased toward a circuit closing position, a first detent operative to maintain said element in an open circuit position when said member is in a normal position, means tending to effect movement of said member to a second position to cause release of said element from said first detent, and means latching said member in its said normal position including a terminal element mounted on and movable relative to said structure and having a second detent operative to latch said member in its said normal position, said terminal element being biased to a position to cause said second detent to release said member and said second detent being held in latching position by mechanical connection of the fuse link in said holder with said terminal element.
22. In an electric cut-out of the circuit reclosing type, a casing having spaced terminals, a fuse assembly removably mounted in said casing and including a fuse holder and a unitary structure for supporting said holder with a fuse link

therein connected between said terminals, said structure including a door for closing an open side of the casing, means arranged to hold said structure substantially fixed in normal position 5 with said door in closed position during fuse operation, a fuse terminal element carried by and movable relative to said structure, circuit reclosing mechanism carried by said structure and including a switching element biased for movement 10 to a circuit controlling position, and means nor-

mally restraining said switching element in another position including a latching detent carried by said movable terminal element, which said detent is maintained in latching position by connection of the fuse link in said holder with 5 said terminal element and said terminal element being movable upon rupture of said fuse link to effect release of said switching element by said detent.

GEORGE F. LINCKS. 10
